UNITED STATES PATENT OFFICE.

GEORGE E. JONES, OF CINCINNATI, OHIO, ASSIGNOR TO WILLIAM AUTEN-
RIETH, OF SAME PLACE.

SURGICAL NEEDLE-HOLDER.

SPECIFICATION forming part of Letters Patent No. 253,209, dated February 7, 1882.

Application filed October 24, 1881. (No model.)

To all whom it may concern:

Be it known that I, GEORGE E. JONES, a citizen of the United States, residing at Cincinnati, in the county of Hamilton and State 5 of Ohio, have invented certain new and useful Improvements in Needle-Holders, of which the following is a specification.

My invention relates to improvements in needle-holders, or "needle-forceps," as they are more properly termed, for use in surgical operations to sew up wounds that cannot well be reached by the hand.

In the accompanying drawings, Figure 1 is an elevation of a needle-holder in its open position. Fig. 2 is an elevation showing it in its closed position, and the movable lever partly inclosed within a sheath. Fig. 3 is a view in section, showing the mechanism for moving the lever forward to close the jaws that hold 15 the needle. This view also shows the device which locks or unlocks the jaws to firmly hold or release the needle, as desired. Fig. 4 is a view in elevation of my needle-holder in a modified form, which is shown in its unlocked 20 or open position.

A is a short arm forming one of the handles of the holder. A' forms the other handle, and is made of one piece the entire length of the instrument, the handle itself being properly 25 shaped at the rear end. The forward part of the handle proper is made to conform to the shape of a rod or shaft the end of which terminates in a jaw, F. Forming a part of this handle A' are pivotal lugs l l, having eyes or 30 perforations in their sides, as shown. It also has a small longitudinal slot, s, between the aforesaid lugs. The forward portion of handle A is formed into an engaging-nose, l', with a transverse perforation, which is inserted 35 between the lugs l l into the slot s, and by means of a pin inserted in the aforesaid holes a hinge is formed and the fastening of one handle to the other is accomplished.

B is a movable rod or shaft held in position 40 by the rings D D, Fig. 1, which are firmly brazed or otherwise attached to handle A', as shown, but which freely allow rod B to move forward or backward. As a substitute for these rings the sheath making part of handle 45 A', as seen in Fig. 2, may be used. This rod B is fitted into the handle A', and at its rear

extremity curved out for the reception of the lug l', attached to handle A. Its forward end is graduated or inclined, as shown.

E is a spring attached to the lever B, near 50 its front extremity.

F' is a serrated jaw pivoted to the rod of handle A.

G is a spring between the haudles, which serves the purpose of readily throwing apart 60 the handles, and thus opening the jaws.

H is a bolt operated by the thumb-piece I, used for locking the handles, and thereby also the jaws containing the needle. This is accomplished by sliding the bolt into a hole, h, 65 contained in a lug, l'', extending from the nose l', as will be more clearly seen in Fig. 3.

e is the screw which holds the thumb-piece I to the bolt H.

The jaws that hold the needle have slots cut 70 in them at different angles, so that the needle may be used at any inclination.

The operation is as follows: The needle is inserted between the jaws F and F', and the operator closes the handles A and A'. The 75 nose l', working within the cut-out portion of rod B, as seen in Fig. 3, forces the said rod forward, and its front end, being tapered or wedge-shaped, is forced under the short arm F', the rear of which is also tapered, and raises 80 it. This has the effect of throwing the forward part of the arm forming the jaw onto the jaw F, and holds the needle securely in its place. If the operator wishes to retain the instrument for any length of time in its closed position, 85 he moves the bolt H forward by means of the thumb-piece I; or, instead of this bolt, an appropriate wedge shaped slide at either end of the handle may be used to accommodate different sizes of needles, thereby throwing it 90 into a keeper for holding it closed. When he wishes to release the needle he withdraws the bolt or slide, the spring G, which is attached for convenience, forces the handles apart, which allows the rod B to return, and the 95 small spring E depresses the rear of arm F', thus throwing it open.

The above-described form may be modified in some respects, as seen in Fig. 4. For instance, the handle A' and the rod B is actuated 100 by a short arm or link intermediate between it and the handle A. Both jaws are beveled

and pivoted to the forward end of the sheath or casing. The rod B is tapered on both its sides, or wedge-shaped, and when actuated by the short arm A is forced between the beveled jaws, thus closing them.

Instead of the bolt heretofore described for locking the instrument, the spring G may be employed for that purpose, as seen in Fig. 4, by simply placing a button, t, on its end, so that it can overlap the handle A or engage with a hook upon its end, such as f.

These instruments are not only useful as needle-holders, but can be employed as forceps for different uses in surgery.

Having thus fully described my invention, I claim—

1. A needle holder or forceps having its working-handle hinged or pivoted to its accompanying handle, and provided with a sliding wedge-bar, which is actuated by the opening and closing of the working-handle, and which bar operates to open and close the gripping jaws, substantially as described.

2. In a needle-holder, the combination of an actuating-lever and shifting-wedge for closing

and opening the jaws, substantially as shown and described.

3. A needle-holder having an elongated handle, the front extremity of which serves as one of the jaws, the arm forming the other jaw 30 being inclined and pivoted thereto, and operated by a shifting-rod beveled for the purpose, which in turn is thrown forward by the closing of one of the handles, substantially as described.

4. In a needle-holder, the combination of the 35 fixed handle, the movable working-handle, the sliding wedge-bar, the clamping-jaws, and the catch or lock for locking the parts when the working-handle is closed, substantially as described.

5. The combination, with a needle-holder, of the rings D D, or their equivalent, to allow actuating-rod B to pass freely back and forth, at the same time holding it securely in position, substantially as described.

GEO. E. JONES.
